UNITED STATES PATENT OFFICE.

PAUL RISSMAN, OF DETROIT, MICHIGAN, ASSIGNEE TO DETROIT INSULATED WIRE COMPANY, OF DETROIT, MICHIGAN, A CORPORATION OF MICHIGAN.

DOORCHECK.

Application filed April 29, 1922. Serial No. 557,295.

To all whom it may concern:

- Be it known that I, PAUL RISSMAN, a citizen of the United States of America, residing at Detroit, in the county of Wayne and 5 State of Michigan, have invented certain new and useful Improvements in Doorchecks, of which the following is a specification, reference being had therein to the accompanying drawings.
- 10 The invention relates to door checks such as are used for limiting the opening of doors of automobiles and for similar purposes, and the invention consists in the novel construction as hereinafter set forth.
- 15 In the drawings:—
- Figure 1 is a horizontal section through a portion of an automobile body and door showing my improved check applied thereto, the door being in closed position;
- 20 Figure 2 is a similar view in the open position of the door;
- Figure 3 is a perspective view of the check detached.
- Figure 4 is a longitudinal section showing 25 the connection through the end portion of the check;
- In the present state of the art it is usual to form door checks, for the purpose above described, of straps of leather or similar 30 material rigidly attached at one end to the door and at the other end to the door casting or frame. When the door is swung open against the check, the inertia is sufficient to throw a considerable stress upon the strap.
- 35 This frequently results in either breaking the strap or tearing it from its attachment. My improved construction is one that can be more cheaply manufactured than the usual constructions and also has the advantage that 40 the shock upon the check is cushioned, thereby lessening the danger of injuries.
- In detail, A is a short section of wire cable or other non-stretchable resiliently flexible material. This cable is preferably covered 45 with a braid or fabric covering B. C and C' are anchor plates, preferably of pressed sheet metal, which, as shown, are in the form of circular disks centrally apertured for the passage of the cable therethrough and having a series of countersunk apertures D for engaging the heads of the securing screws E. Surrounding the central aperture in each disk is a flange F which forms a bearing for the cable. At one end of the cable the 50 plate C is rigidly attached, preferably by inserting a screw G, which spreads the strands of the cable and securely clamps the same against the flange F. This clamping is rendered more secure by flaring the flange F, as shown, so that the insertion of the 55 tapering screw will produce a wedging effect. The other anchor plate C' is loosely 60 slideable upon the cable and a yielding abutment is formed for this plate by a spring H sleeved upon the cable and a flaring collar I, which is secured to the end of the cable by a screw J in a similar manner to the securing of the anchor plate C.
- With the construction as described, in applying the same to a door, one of the plates 70 such as C is secured to the door frame post K, while the other plate C' is secured to the post L of the door. The former post is bored at M for the passage of the projecting portion of the cable, together with a spring 75 H and collar I. Thus, when the door is closed, the plates C and C' will be in proximity and the cable, spring and collar will extend through the bore M. On the other hand, when the door is swung open, the cable 80 will be drawn through the plate C' until the spring H abuts against the flange F. The further movement of the door will compress the spring and will cushion the shock.
- The construction described can be manufactured at small cost and will have a long 85 life, inasmuch as the flexing of the cable is within the elastic limit of the material. It is also a simple operation to attach the check to a door.
- 90 What I claim as my invention is:
1. A door check comprising anchor plates oppositely secured to the posts of the door and door frame, a non-stretchable stranded cable passing through apertures in said plates and through an aligned aperture in one of said posts, a ferrule or collar surrounding each end portion of the cable, and a wedge inserted centrally in the end of the cable for clamping the same to said collar or 95 ferrule.
2. A door check comprising anchor plates secured respectively to the posts of the door and door frame, a stranded cable passing through central apertures in said plates and 100 through an aligned aperture in one of said posts, collars or ferrules surrounding the opposite ends of the cable, one of said collars being integral with one of said plates, and a member inserted in the end of the 105 cable for clamping the same to said collar or ferrule.
- 110

cable for wedging the strands thereof against said collar or ferrule to securely clamp the same.

3. A door check comprising anchor plates oppositely secured to the posts of the door and door frame, a resilient stranded cable extending through apertures in said plates and an aligned aperture in one of said posts, collars or ferrules surrounding the ends of said cable, and screws inserted into the ends of the cable to spread the strands thereof and to wedge the same into clamping engagement with said collars or barrels.

4. A door check comprising anchor plates oppositely secured to the posts of the door and door frame, a stranded cable extending through apertures in said plates, and an aligned aperture in one of said posts, collars or ferrules surrounding the end portions of

said cable, one of said collars being integral with one of said plates, screws for engaging the ends of said cables to wedge the strands thereof into clamping engagement with said collars or ferrules, and a spring sleeved on said cable intermediate one of said collars or ferrules and the adjacent anchor plate.

5. A door check comprising anchor plates secured respectively to the posts of the door and door frame, a cable passing through apertures in said plates and through an aperture in one of said posts, collars surrounding the opposite end of the cable, one of said collars being integral with one of said plates, and means for securing the ends of the cable to said collars.

In testimony whereof I affix my signature.

PAUL RISSMAN.
